(57) The ornamental design for a pair of temple arms for an eyeglass frame, as shown and described.

DESCRIPTION

FIG. 1 is a perspective view of a pair of temple arms for an eyeglass frame for my new design shown in the environment of an eyeglass frame;

FIG. 2 is a front elevational view thereof;

FIG. 3 is a rear elevational view thereof;

FIG. 4 is a side elevational view, wherein the other side is a mirror image thereof;

FIG. 5 is a top plan view thereof;

FIG. 6 is a bottom plan view thereof; and,

FIG. 7 is a perspective view thereof shown in an exploding format.

The broken lines showing the front of the eyeglass frame are for the purpose of illustrating environment structure and form no part of the claimed design.
